UNITED STATES PATENT OFFICE.

OSIAS O. KRUH, OF SCHENECTADY, NEW YORK, ASSIGNOR TO GENERAL ELECTRIC COMPANY, A CORPORATION OF NEW YORK.

PROTECTING MERCURY-VAPOR APPARATUS.

1,076,212.

Specification of Letters Patent.

Patented Oct. 21, 1913.

Application filed September 20, 1907. Serial No. 393,815.

To all whom it may concern:

Be it known that I, OSIAS O. KRUH, a subject of the Emperor of Austria-Hungary, residing at Schenectady, in the county of Schenectady and State of New York, have invented certain new and useful Improvements in Protecting Mercury-Vapor Apparatus, of which the following is a specification.

10 In the operation of high voltage mercury arc rectifiers, such, for example, as are used for supplying constant current circuits containing arc lamps in series, the starting of the rectifier is usually effected by means of 15 starting anodes, ordinarily of mercury, arranged adjacent to the cathode. These starting anodes, after the apparatus is once put into operation, are not usually continued in operation. When such a system is working 20 it has been observed that high potential discharges sometimes occur between the cathode and the starting anodes. It then frequently happens that the cathode spot, or in other words, the point on the main 25 cathode from which the main rectifier arc emanates, shifts over from the cathode to one of the starting anodes. The main arc current therefore passes through this anode and may cause more or less considerable 30 overheating of the corresponding parts of the exciting circuit which are not intended for this current. Moreover, the mercury of the starting anodes in course of time may be boiled away and the glass fractured. Also 35 it sometimes happens that the high voltage discharge between the cathode and the anodes is so severe as actually to puncture the glass of the rectifier tube.

The high voltage appearing between the 40 starting anodes and the cathode appears to be due to oscillations or high frequency effects caused by the interaction of the capacity and inductance of the system with its arc lighting load. I have found that the 45 shifting of the cathode spots and its attendant evils, all of which appear to be caused in one way or another by the high potentials produced in the neighborhood of the cathode and the starting anode, may be 50 obviated by surrounding the cathode and the starting anodes by shells of metal or other good electrically conducting material. This arrangement neutralizes any tendency 55 for the cathode spot to jump to one of the starting anodes, and it also prevents the

building up of any high difference in potential between the cathode and one of the starting anodes, and so avoids any danger of puncture of the glass by a high potential discharge between these parts.

60 The novel features which characterize my invention I have endeavored to point out in the appended claims. The invention itself, as embodied in practice, will perhaps be better understood by reference to the following description taken in connection with the accompanying drawings, in which—

Figure 1 shows a system embodying my invention; and Fig. 2 a modified form of 70 protecting device.

In Fig. 1 the source of supply for the 75 rectifier system therein indicated is shown as consisting of a constant current transformer having a primary coil 1 and a secondary coil 2, movable with respect to the primary. The transformer may be of any usual type and requires no special description. The secondary winding 2 is provided with three taps connected to mains 3, 4 and 5. Mains 3 and 5 which extend to the 80 rectifier as will be described, are connected to the outer terminals of the coil 2, while the main 4 is connected at or near the electrical center of the winding.

The rectifier tube is shown at 6 and may, 85 of course, vary widely in shape. In the particular form shown, however, two outwardly and upwardly extending arms 7 and 8 are provided in which the main anodes 9 and 10 are located. At the bottom of the 90 rectifier tube are three pockets filled with mercury to constitute three electrodes 11, 12 and 13 in the usual way. The middle body 12, forms the cathode of the rectifier while the mercury in the pockets 11 and 13 constitutes the starting anodes.

The load circuit indicated by a series of 95 arc lamps at 14 is connected to the main 4 at one end and to the cathode 12 at the other. An inductance coil 15 in series with this 100 load circuit serves to smooth the current and to steady the operation of the system.

Current for the starting anodes 11 and 13 is supplied from a constant potential source of moderate voltage, such for example as 105 the small step-down transformer 16. The outer terminals of the secondary 17 of this transformer are connected, as indicated, to the starting electrodes 11 and 13, while the middle of this winding 17 is connected 110

through inductance 18 to the cathode 12. By shaking the rectifier tube 6 mercury is caused to flow temporarily between the cathode and one or more of the starting anodes and thus initiates the starting arcs in a manner well understood. The main circuits of the rectifier proper, if not already closed, may then be closed and the starting arcs from the cathode will cause the main arcs in the rectifier to start. The apparatus being thus started into operation it may happen that from various causes, some of which are more or less obscure, high voltages are produced between the cathode 12 and the anodes 11 and 13, as described, so that discharges sometimes occur from the cathode 12 to one of the other of the anodes 11 and 13. When this happens a new cathode spot is frequently or generally produced at the surface of the starting anode and the main cathode spot immediately shifts over to the new cathode spot in the starting anode, with results which may in some cases be disastrous to the tube. I have found that all this may be prevented by surrounding the region of the cathode and the starting anodes by electrical circuits of good conductivity, such, for example, as the closed circuits 19 of sheet metal, such as copper. This member 19 may consist for example, of tinfoil surrounding the glass portion of the tube immediately over the cathode and the starting anodes, but out of connection with the leading-in conductors, or it may consist of heavier sheet metal formed into a shell surrounding the respective electrode chambers. Instead of metal in sheet form used for the purpose indicated, I may in some cases simply twist wire about the electrode-containing legs of the tube, as indicated at 20, in Fig. 2. In this case the wire is simply interlaced around the three legs and twisted together. It is possible that the metal surrounding the electrode chambers operates in the nature of a short-circuited secondary to oppose or damp out the oscillations or high frequency effects which tend to produce discharges from the cathode to the adjacent anode. There is reason, however, for thinking that the trouble described is due to an accumulation of high potential charges on the surface of the rectifier tube in the vicinity of the electrodes in question. The presence of metal electrically connecting these regions therefore, serves to equalize the static charges and so prevents the jumping of current from the cathode to a starting anode. Whatever, however, may be the true explanation of the reasons for the shifting of the cathode spot, I have found that the trouble may be prevented by the means indicated. Therefore, while I have given my present understanding of the operation of

my invention, I do not wish to be limited to any particular theory since the beneficial effects of my invention may be obtained, regardless of what view may be entertained as to the theory of operation.

What I claim as new and desire to secure by Letters Patent of the United States, is,

1. The combination of a rectifier tube having main operating electrodes consisting of a cathode and anodes, starting electrodes arranged adjacent to the cathode, and an electrical conductor surrounding the cathode and the starting anodes but out of electrical contact therewith.

2. In a vapor electric device, the combination of an exhausted tube having a cathode, a starting anode located adjacent thereto, and means for preventing the cathode spot from shifting to said anode by equalizing the static stress between said cathode and anode.

3. In a mercury vapor rectifying apparatus, the combination of a rectifier tube having main operating electrodes and starting electrodes, and electrically conducting circuits in proximity to the main negative electrode and the starting electrodes for preventing the shifting of the cathode spot from the negative electrode to either of the starting electrodes.

4. In a mercury vapor apparatus, the combination of an evacuated tube, a negative electrode, an auxiliary or starting electrode electrically connected therewith during the operation of said apparatus, and means adjacent to said negative electrode for preventing abnormal electrical discharges between the cathode and starting electrode to prevent the starting electrode from operating as a negative electrode to the exclusion of said negative electrode.

5. In a mercury vapor device, the combination of a main anode and a coöperating cathode, a starting anode having a tendency to operate as a sustained cathode by the shifting of the arc to the starting anode from the regularly operating cathode, and inductive means external to said cathode for restraining that tendency.

6. In a vapor electric device, the combination of an exhausted tube having a cathode, a starting anode located adjacent thereto, and a closed circuit of low resistance for equalizing the static stress between said cathode and anode by damping out high frequency effects.

7. In a vapor electric device, the combination of an exhausted tube having a cathode, starting anodes adjacent thereto, current supply wires for said device, and a conductor insulated from said wires and forming a closed circuit of low resistance in inductive relation to said cathode and anodes.

8. The combination of a source of high potential current, a vapor electric device

having a cathode, a main anode or anodes and a starting anode electrically connected to said source and means for preventing disturbing electrical conditions at the cathode and starting anode which would tend to cause the latter to become a sustained cathode.

9. The combination of a high potential transformer, a vapor electric device connect-
10 ed thereto having main coöperating elec-
trodes and a starting electrode electrically connected to the cathode through an inductive path of relatively low resistance, and
15 electrically conducting circuits in proximity to the main negative electrode and the start-

ing electrode for preventing disturbances tending to cause the starting electrode to operate as a sustained cathode.

10. A current rectifying device comprising a mercury containing receptacle of insulating material, and a band of conducting material on the exterior thereof, said band being independent of the circuits of the device.

In witness whereof, I have hereunto set my hand this 18th day of September, 1907.

OSIAS O. KRUH.
